UNITED STATES PATENT OFFICE.

FRANK DOCHNAL, OF ST. LOUIS, MISSOURI.

BRICK CHIMNEY STRUCTURE.

1,156,468.

Specification of Letters Patent.

Patented Oct. 12, 1915.

Application filed May 2, 1914. Serial No. 835,880.

To all whom it may concern:

Be it known that I, FRANK DOCHNAL, a citizen of the United States, residing at St. Louis, in the State of Missouri, have invented certain new and useful Improvements in Brick Chimney Structures, of which the following is a specification.

My invention relates to an improved wall structure particularly, a chimney wall structure.

The invention aims to provide a structure having an inner or an outer lining or both of brick of such construction that linings or walls will be securely bound to intermediate concrete or equivalent material against cracking or crumbling through the action of heat; the bricks so secured as to be fastened against displacement, being connected by a specific tying element consisting of rings or endless rods in addition to vertical stay rods; the bricks having coöperating grooves to receive the rings and binding material and the brick also being constructed so that the binding material while in a plastic state may readily enter the grooves and the bricks remain in place even should they sever from the binding material.

From the following description taken in connection with accompanying drawings the foregoing and additional objects and advantages will appear.

In said drawings;—Figure 1 is a fragmentary elevation of a chimney constructed in accordance with my invention; Fig. 2 is a fragmentary enlarged cross sectional view of the chimney; Fig. 3 is a cross sectional view on line 3—3 of Fig. 2; Fig. 4 is a cross sectional view on line 4—4 of Fig. 2; Fig. 5 is an enlarged detail perspective view of one of the bricks employed; Fig. 6 is a vertical section through one of said bricks; and Fig. 7 is a detail on one of the stay rings employed.

Referring specifically to the drawings the chimney or other wall structure may be built upon a concrete or other base 1. The wall essentially comprises an inner lining and an outer lining, both built of bricks 2, and a binding body 3 of concrete or other plastic material in connection with which binding before hardening thereof, the bricks are laid.

Said bricks are similar in construction but both linings and in use are of such size as particular requirements demand. The outer and inner walls 4 and 5 respectively preferably curved or arcuate and the side walls are inclined or slanting at 6 and concave or grooved at 7. Also the upper and lower faces of the bricks are grooved or concaved at 8 to retain stay rings 9. Further openings 10 extend vertically through the bricks to receive stay rods 11 which rise from the base 1.

In erecting the chimney or other walls the bricks are slid onto the rods 11 until a complete layer is laid, whereupon cement or concrete is tamped or placed between the bricks and thereupon the rings 9 are properly placed and then sufficient concrete placed over them to fill the grooves 8 of the next higher row of bricks. Previously a ring and cement may be placed to fill the grooves 8 of the lower faces of the lowermost bricks. It will be realized that by reason of the particular shape of the bricks the plastic material can be placed or tamped between them and into the grooves 8 as it is often desirable to tamp the material into the grooves after a succeeding row of bricks has been laid. Due to the fact that the grooves 8 are provided and received the endless wires 9, it will be realized that the rings or wires 9 when the wall or filling 3 has hardened join the bricks and secure the bricks against displacement diametrically of the chimney. While the rods 11 would tend to prevent the diametric displacement of the bricks the result is better accomplished with the rings and grooves as the rings and grooves relieve the rods 11 of strain, and they serve essentially to guide means in assembling and laying the bricks. One or more rods 12 may extend upwardly from the base 1 and be layed in the filling 3 to secure greater rigidity for the structure.

I desire it to be understood that I may vary the construction illustrated and described within the spirit and scope of the following claim:—

A wall structure having a horizontally 100 endless central plastic wall, stay members fastened therein, linings of bricks, one on

the exterior and the other on the interior of said wall, vertical stay members passing through said bricks, said bricks being reduced inwardly by the provision of inclined walls and grooves at the sides thereof, said bricks being provided with grooves on their upper and lower faces communicating with the grooves at the side thereof to receive

plastic material and endless stay members in said grooves and material therein.

10

In testimony whereof I affix my signature in presence of two witnesses.

FRANK DOCHNAL.
